UNITED STATES PATENT OFFICE

90,887

DESIGN FOR A BED

Christian R. Kayser, Los Angeles, Calif.

Application July 31, 1933. Serial No. 48,898

Term of patent 3½ years

To all whom it may concern:

Be it known that I, CHRISTIAN R. KAYSER, a citizen of the United States, residing at Los Angeles, in the county of Los Angeles and State of California, have invented a new, original, and ornamental Design for a Bed, of which the following is a specification, reference being had to the accompanying drawing, forming a part thereof.

The figure is a perspective view of the bed, showing my new design.

I claim:

The ornamental design for a bed, as shown.

C. R. KAYSER.
